CORPORATION STOP AND TOOL

Frank H. Mueller, Walter J. Bowan, and Elmer H. Fawley, Decatur, Ill., assignors to Mueller Co., Decatur, Ill., a corporation of Illinois

Application October 15, 1938, Serial No. 235,246

5 Claims. (Cl. 81—53)

This invention relates to a tool for use in turning to or from position bodies such as corporation stops and the like.

The usual corporation stop comprises a body, which houses a valve, and oppositely projecting threaded nipples of which one is intended to be threaded into an aperture in a main and the other to receive a coupling. In common practice, for the purpose of inserting a stop, a tool is applied to the coupling nipple, the tool having a threaded socket in which the nipple is fully engaged. Since considerable torque is required in turning the stop home, the coupling nipple becomes jammed in the socket with the result that the stop will sometimes follow the tool when it is sought to remove the latter, and, moreover, the coupling nipple itself may become injured.

It is an object of this invention to overcome these objectionable features of prior usage by providing means on the tool for positively transmitting rotation of the latter to the stop body independently of the coupling nipple. This torque transmission occurs in the absence of full engagement of the nipple in the socket, and, consequently, the tool may be readily removed with no danger of the stop following it and the danger of injury to the nipple is eliminated.

The invention also relates to an improved form of stop body whereby superior cooperation with an inserting tool of the general type herein contemplated, and particularly with the specific tool to be hereinafter described, is secured.

Preferred embodiments of the new stop and tool are shown in the accompanying drawing in which:

Figure 1 is an elevation of the stop with the tool operatively applied thereto for an inserting operation. A portion of a main is shown in cross section;

Figure 2 is a section substantially on line 2—2 of Figure 1;

Figure 3 is a section of the tool on line 3—3 of Figure 2;

Figure 4 is a section substantially on the line 4—4 of Figure 1;

Figure 5 is a plan view of the tool; and

Figure 6 is an elevation of a portion of the tool.

Referring to the drawing, the stop is generally indicated at 10 and the tool at 11. The stop comprises a body 12 in which a plug 13 is rotatable for the control of flow through the stop. A threaded nipple 14 projects from one end of the body and is intended to be engaged in a threaded opening as at 15 in a main 16. Coaxial with nipple 14 is a threaded coupling nipple 17.

Immediately at the base of the nipple 17, the body has a polygonal, preferably squared, portion 18 having faces of substantial axial extent.

The tool 11 comprises a shank 19 which is ordinarily of tapered form, is axially grooved as at 20', and may be otherwise equipped for engagement in the socket of the usual boring bar.

Coaxial with the shank portion and, as here shown, integral therewith, is a cylindrical head 20 which includes a reduced cylindrical end extension 21, and formed in the head is an axially threaded socket 22 which desirably has a depth greater than the length of the nipple 17. The head is provided with diametrically opposite axially extending grooves 23 and 24 which are open toward the shank, but which have walls 25 and 26, respectively, at their other ends.

Slidable on the head 20 is an annular member 27 which is desirably externally knurled. Member 27 includes an inwardly projecting flange 28 which is slidable on extension 21. Said member is also provided with diametrically opposite axially extending grooves 29 and 30 in the ends of which, opposite flange 28, are secured blocks or splines 31 and 32 by means of screws 33 and 34, these splines substantially filling the grooves cross-sectionally and serving the dual function of preventing rotation of member 27 relative to head 20 and of limiting sliding movement of the former relative to the latter in the opposite direction from the shank by abutment of the stops with the end walls 25 and 26. Sliding movement of member 27 relative to head 20 in the other direction is limited by the engagement of flange 28 with a shoulder 35 at the inner end of extension 21.

Desirably, although not necessarily, yieldable means is interposed between flange 28 and head 20 so that the parts are normally yieldingly held in the expanded relation shown in Figures 1 to 3. For this purpose, compression springs 36 and 37 may be disposed in diametrically opposite axially extending bores 38 and 39 in head 20, bearing at one end against the blind ends of these bores and at the other end against flange 28 through the intermediary of pins 40 and 41. The outer ends of the springs bear against the heads of the pins and the shanks of the latter, which extend into bores 38 and 39 at all times, prevent buckling of the spring portions which are outside of the bores.

On its end surface remote from shank 19, member 27 is provided with one or more abutments projecting therefrom in the opposite direction from the shank. As here shown, two

abutments 42 and 43 formed integral with the head are provided. These abutments are diametrically opposite each other and have parallel opposed faces 44 and 45 symmetrical to the tool axis and spaced apart a distance somewhat greater than the length of a side of the squared body portion 18. The trailing portions of abutments or lugs 42 and 43 are beveled to provide cam surfaces 46 and 47 which merge into the normal plane of the outer face of member 27. In the normal expanded relation of parts, the lugs 42 and 43 project substantially wholly beyond the outer end of extension 21. When member 27 is moved relative to head 20 toward shank 19, flange 28 will eventually abut shoulder 35 as above mentioned, and in this relation of parts, the outer extremities of lugs 42 and 43 are preferably substantially flush with the outer end of extension 21.

In applying the tool to the stop, member 27 is manually moved to the last mentioned relation and held while socket 22 is threaded on nipple 17. Before the nipple has become fully engaged in the socket, member 27 is released so that lugs 42 and 43 are projected toward the stop body, and if the tool and stop are in a proper angular relation, the lugs will take an overlying relation to opposite faces of the squared portion 18, and will engage these faces, or the corner portions thereof, to impart rotation of the tool to the stop in the threading direction. The stop is thus positively driven without any jamming of nipple 17 in socket 22.

When the stop has been screwed home, the tool is reversely rotated, cam surfaces 46 and 47 riding over the corners of the squared portion and freeing the lugs so that the tool is readily removable.

It will be understood that in a tool designed for removing stops, the lugs will be reversed. Consequently, in applying the tool, the lugs will ride over the corners of the squared portion due to the provision of the cam surfaces as at 46 and 47. When the tool has been sufficiently applied, reverse rotation will cause the lugs to positively engage opposite faces of squared portion 18 so that the stop will be forced to rotate with the tool.

It will be understood that we do not limit ourselves to the specific embodiments of the tool and plug herein disclosed, since variations in form and arrangement are possible without departure from the invention. Moreover, we wish to make it clear that the new tool is not limited to use with the new form of stop herein disclosed, and vice versa, although the two cooperate in the most effective manner and consequently are desirably used together.

We claim:

1. A tool for use in turning a corporation stop, said stop including a body and threaded nipples projecting from opposite ends of said body, said body having a squared portion at the base of one of said nipples, said tool comprising a shank portion and a head portion at one end of the shank portion having a threaded socket therein coaxial with said shank portion and engageable with said one of said nipples, a member embracing said head portion and reciprocable relative thereto on the axis of said shank portion between limit positions, means preventing rotation of said head portion and member relative to each other, and an abutment projecting from said member in the opposite direction from said shank portion and beyond said head portion when

said member is at its limit of reciprocation remote from said shank portion, said abutment being engageable with a face of said squared portion to transmit rotation of the tool to the stop in one direction while said one of said nipples is less than fully engaged in said socket, said abutment having a cam surface engaging the edge of said face upon reverse rotation of said tool relative to said stop whereby to free the abutment and permit continued reverse rotation of the tool.

2. A tool for use in turning a corporation stop, said stop including a body and threaded nipples projecting from opposite ends of said body, said body having a squared portion at the base of one of said nipples, said tool comprising a shank portion and a head portion at one end of the shank portion having a threaded socket therein coaxial with said shank portion and engageable with said one of said nipples, a member embracing said head portion and reciprocable relative thereto on the axis of said shank portion between limit positions, means preventing rotation of said head portion and member relative to each other, and abutments projecting from diametrically opposite points of said member in the opposite direction from said shank portion and beyond said head portions when said member is at its limit of reciprocation remote from said shank portion, said abutments being engageable with opposite faces of said squared portion to transmit rotation of the tool to the stop while said one of said nipples is less than fully engaged in said socket, said abutments having cam surfaces engaging the edges of said faces upon reverse rotation of said tool relative to said stop whereby to free the abutments and permit continued reverse rotation of the tool.

3. A tool for use in turning a corporation stop, said stop including a body and threaded nipples projecting from opposite ends of said body, said tool comprising a shank portion and a cylindrical head portion at one end of said shank portion coaxial with the latter, said head portion having a coaxial threaded socket therein engageable with one of said nipples, an annular member slidable on said head portion, an axially extending groove in said head portion having an end wall, a spline fixed to said member and engaged in said groove whereby to limit relative sliding movement in one direction and to prevent relative rotation of said member and head portion, means limiting relative sliding movement in the other direction, said head portion being provided with spring pockets, compression springs in said pockets and acting to urge said annular member to its limit away from said shank portion, and an abutment projecting from said member in the opposite direction from said shank portion and beyond said head portion when said member is at its limit of reciprocation remote from said shank portion, said abutment being engageable with a portion of said stop to transmit rotation of the tool to the stop while said one of said nipples is less than fully engaged in said socket, said abutment having a cam surface engaging the edge of said face upon reverse rotation of said tool relative to said stop whereby to free the abutment and permit continued reverse rotation of the tool.

4. A tool for use in turning a corporation stop, said stop including a body and threaded nipples projecting from opposite ends of said body, said body having a squared portion at the base of one of said nipples, said tool comprising a

shank portion having a threaded socket therein coaxial with said shank portion and engageable with said one of said nipples, a member embracing said head portion and reciprocable relative thereto on the axis of said shank portion between limit positions, means preventing rotation of said head portion and member relative to each other, and abutments projecting from diametrically opposite points of said member in the opposite direction from said shank portion and beyond said head portions when said member is at its limit of reciprocation remote from said shank portion, said abutments having opposed parallel side faces spaced apart so as to lie along opposite faces of said squared portion to engage the same to transmit rotation of the tool to the stop while said one of said nipples is less than fully engaged in said socket, said abutments having inclined end faces engaging the end edges of the faces of said squared portion upon reverse rotation of said tool relative to said stop whereby to free the abutments and permit continued reverse rotation of the tool.

5. A tool for use in turning corporation stops, said stops including a body and threaded nipples projecting from opposite ends of said body, said body including a side portion adjacent one of said nipples faced oppositely to the threading

direction of the latter, said tool comprising a shank portion and a head portion at one end of the shank portion having a threaded socket therein coaxial with said shank portion and engageable with said one of said nipples, and a retractile abutment rectilinearly reciprocable in the axial direction of the tool and projectable beyond the head portion in the opposite direction from said shank portion; said abutment being maintainable in retracted relation so that its leading edge will clear said side portion as the socket is threaded on said one of said nipples and being then projectable so that its leading edge will firmly engage said side portion as threading of the socket on said one of said nipples continues and prior to such full reception of said one of said nipples in said socket as would cause jamming, whereby to positively transmit rotation of the tool of the stop in the inserting direction of the latter; said abutment due to its retractility riding over any body portion encountered by it upon reverse rotation of the tool relative to the stop so that the tool is readily removable from the stop.
